Edgar Hale Co.

UNITED STATES PATENT OFFICE.

PATRICK M. SCANLAN, OF BROOKLYN, NEW YORK.

AIR-PUMP.

1,385,497.

Specification of Letters Patent. Patented July 26, 1921.

Application filed September 10, 1919, Serial No. 322,817. Renewed January 27, 1921. Serial No. 440,529.

To all whom it may concern:

Be it known that I, PATRICK M. SCANLAN, a citizen of the United States, and residing at Brooklyn, in the county of Kings and 5 State of New York, have invented certain new and useful Improvements in Air-Pumps, of which the following is a specification, such as will enable those skilled in the art to which it appertains to make and 10 use the same.

This invention relates to air pumps and particularly to devices of this class designed for use in inflating pneumatic tires, and the object thereof is to provide an air pump 15 which is simple in construction, efficient in operation and which can be operated more conveniently or easily than other devices of its class and with the exertion of a minimum effort or power; a further object being to 20 provide a portable pump which involves foldably connected parts which may be compactly folded together when not in use; and with these and other objects in view the invention consists in an air pump constructed and operated as hereinafter described and claimed.

The invention described and claimed herein is an improvement on that described and claimed in a prior patent granted to me 30 April 22, 1919, and numbered 1,301,751; and is fully disclosed in the following specification, of which the accompanying drawing forms a part, in which the separate parts of my improvement are designated by suitable reference characters in each of the 35 views, and in which:

Figure 1 is a side view of a pump and indicating the operation thereof, and with part of the construction broken away and in 40 section;

Fig. 1^a is a view similar to Fig. 1 but showing only a detail of the construction on an enlarged scale, and showing such detail in section;

Fig. 2 is a partial section on the line 2—2 of Fig. 1;

Fig. 3 is a partial section on the line 3—3 of Fig. 2 and on an enlarged scale;

Fig. 4 is a partial section on the line 4—4 of Fig. 1 and on an enlarged scale; and,

Fig. 5 is a partial section on the line 5—5 of Fig. 1 and on an enlarged scale.

In practice, I provide a base 10 which is stamped from sheet metal and is approximately U-shaped in form, or comprises parallel side members 11 joined at one end by

an integral cross head 12 and the free ends 13 of the side members 11 are connected by a transverse pin or bolt 14, which forms a pivotal connection for a lever 15 with the 60 base 10.

The lever 15 is also preferably stamped from sheet metal and is of U-shaped form, or comprises parallel side members 16 joined at one end by an integral cross head 17, and the free ends 18 of which are rotatably mounted on the pin or bolt 14, as clearly shown in Fig. 2. A transverse plate 19 is secured or mounted between the side members 16 of the lever 15 adjacent to the 70 cross head 17, and which in combination with said cross head forms a support for a detachable handle member 20, the inner end of which is provided with a rod 21 which passes through the cross head 17, and 75 is threaded into the transverse plate 19, as clearly shown in Fig. 1.

Pivoted to the base as shown at 22 is a supplemental base member 23 composed of two similarly formed strips 24 joined at 80 their free ends by a cross rod 25. A yoke-shaped member 26 is rotatably mounted on the rod 25 between the sides 24 of the supplemental base member 23, and mounted in connection with said yoke-shaped member 85 26 is a cylinder frame member 27 in which a pump cylinder 28 is mounted.

The frame member 27 is stamped from sheet metal and consists of parallel side members 29 joined at the top by an integral cross head 30 and to the base of which is secured a transverse plate 31 which joins the free ends of the side members 27. The lever 15, or the side members 16 thereof, are pivotally connected to the side members 90 29 of the frame member 27 by bolts 32 passed therethrough, as clearly shown in Figs. 1 and 5.

The cylinder 28 is closed at its upper and lower ends by cap plates 33 and 34, and a 100 tubular piston rod 35 is adapted to pass through the cap plate 34 into the cylinder 28, and mounted on said piston rod within the cylinder is a piston 36. The protruding end of the piston rod passes through a bushing construction which consists of an inner sleeve nut 37, to which is secured an outer sleeve nut 38, the latter sleeve nut being adjustably mounted in the cross plate 31 of the frame member 28, this construction being clearly shown in Fig. 1. The piston rod 105 also passes through the cross head 39 of

the yoke-shaped member 26 and into a coupling member 40, and said rod is held in engagement with the yoke-shaped member 26 and coupling 40 by a lock nut 41, as 5 clearly shown in Fig. 3. A flexible pipe coupling 42 is connected with the coupling member 40, whereby a rubber hose may be connected with and placed in communication with said coupling member 40 in the 10 usual manner.

The piston 36, in the form of construction shown, is made up of a plurality of fibrous strips or disks 43, 44 and 45, the disks 43 and 45 being preferably composed of cork 15 or felt, while the strip 44 is preferably composed of leather, and these strips or disks are held in position by a plurality of metal disks 46, which are mounted on the inner end portion of the tubular piston rod and 20 held in place by a nut 47 secured to said rod. A valve device 48 is mounted in the inner end portion of the rod 35, said valve device being provided with a valve member 49, which is adapted to control the passage 25 of air from the cylinder into and through said tubular piston rod through ports or passages 50 in said valve device.

A catch and lock device 51 is pivoted to the inner face of one of the sides 11 of the 30 base 10, as shown in Figs. 2 and 3, said device being provided with two nose portions 52, one of which is adapted to operate in connection with a pin 53 mounted on the free end portion of one of the sides 24 of the 35 supplemental base member 23, and the other of which is adapted to operate in connection with a pin 54 secured to the side 11 with which the device 51 is connected. The catch and lock device 51 serves to hold the supplemental base member 23 in the position shown in full lines in Figs. 1 and 3, while the 40 pump is in operation, but will permit of the folding of said supplemental base member 23 into the position shown in dotted lines in Fig. 3, in folding the separate parts of the 45 pump together.

The distinctive features of this construction over that shown and described in the 50 patent hereinbefore referred to, are the supplemental base member 23, the connection of the pump mechanism involving the frame 27, cylinder 28 and piston rod 35 with the base 10, or said supplemental base and the connection of the lever 15 with the frame 27, 55 whereby it will be seen that a greater lever stroke is obtained at a greater leverage thus producing a more powerful pump mechanism. By providing the supplemental base member 23, the various parts of the pump 60 involving the lever 15, the frame 27 and cylinder 28 may be compactly folded together as is partially indicated in dotted lines in Fig. 1, as well as in Fig. 3, it being understood that the handle member 20 is detached 65 from the lever 15 in this operation.

It will also be apparent that while I have shown a specific form of piston and valve device mounted in the inner end portion of the tubular piston rod, that my invention is not limited to this construction, nor to the 70 various other details of construction herein shown and described, and changes therein and modifications thereof may be made, within the scope of the appended claims, 75 without departing from the spirit of my invention or sacrificing its advantages.

It will also be seen that another distinctive feature of this invention over that described in my prior patent lies in the construction of the base 10 of a single strip of 80 material bent into approximately U-shaped form, the free ends of which are joined by a pin or bolt and the central portion of which is reinforced by a U-shaped strip 55, which is riveted or otherwise secured to the 85 sides 11 of the base 10, as is illustrated in Figs. 2 and 3. This openwork construction simplifies the manufacture of the base and also cheapens the cost thereof by reason of the saving of material as will be apparent. 90 It will also be noted that the sides 11 are recessed at the top as shown at 56 to form a foot rest in the use of the pump, it being understood that the operator places one or both feet upon the base 10 to hold it in proper 95 position, while the lever 15 is operated by hand.

Having fully described my invention, what I claim as new and desire to secure by Letters Patent, is:—

1. A device of the class described comprising a base, and an air pump mechanism involving a pump cylinder, a piston in said cylinder and a rod connected with said piston and passing out through one end of said cylinder, a supplemental base movably mounted in said base, means for pivotally connecting the protruding end of the piston rod in connection with said supplemental base, and an operating lever pivoted to the base and pivotally connected with said pump mechanism.

2. A device of the class described comprising a base, a supplemental base movably mounted therein, a pump mechanism involving a pump cylinder, a piston in said cylinder and a rod connected with said piston and passing out through one end of said cylinder and pivoted to said supplemental base, a frame member in which said cylinder is mounted, and a lever pivoted to said base and pivotally connected with said frame member.

3. A device of the class described comprising a base, a supplemental base pivotally mounted in connection therewith, a pump mechanism involving a cylinder, a piston in said cylinder, and a tubular rod connected with said piston and passing out through one end of said cylinder, a yoke-shaped mem- 130

ber pivotally mounted in connection with said supplemental base and to which the protruding end of said piston rod is connected, a frame member in which said cylinder is mounted, a lever pivotally connected with said base and provided at its free end with a detachable handle member, and means for pivotally connecting said lever with said frame member below the central portion of the cylinder.

4. A device of the class described comprising a base, a supplemental base pivotally mounted in connection therewith, a pump mechanism involving a cylinder, a piston in said cylinder, and a tubular rod connected with said piston and passing out through one end of said cylinder, a yoke-shaped member pivotally mounted in connection with said supplemental base and to which the protruding end of said piston rod is connected, a frame member in which said cylinder is mounted, a lever pivotally connected with said base and provided at its free end with a detachable handle member, means for pivotally connecting said lever with said frame member below the central portion of the cylinder, and a coupling member mounted in connection with said pivoted yoke-shaped member and with which a flexible hose is adapted to be connected.

5. A device of the class described comprising a base, a supplemental base member pivotally mounted in connection with said base, means for locking said supplemental base member in connection with said base in one position thereof, and means for pivotally connecting a pump mechanism with said supplemental base member.

6. A device of the class described comprising a base, a supplemental base member pivotally mounted in connection with said base, means for locking said supplemental

base member in connection with said base in one position thereof, means for pivotally connecting a pump mechanism with said supplemental base member, said pump mechanism involving a cylinder, a piston in said cylinder and a tubular rod connected with said piston and passing out through one end of said cylinder, and a lever pivoted to said base and in operative connection with said cylinder.

7. A pump device of the class described comprising a substantially U-shaped base, a supplemental base member pivotally mounted between the sides of said base adjacent to the cross head end thereof, a lever pivotally mounted in connection with the free ends of the sides of said base, a pump mechanism involving a cylinder, a piston and a rod connected with said piston in passing out through one end of said cylinder, a frame member in which said cylinder is mounted, means for pivotally connecting said lever with said frame member, means for pivotally connecting the protruding end of said rod with said supplemental base member, said supplemental base member being adapted to be moved into two positions within said base in folding the separate parts of the pump together and extending the same when in use, and a catch device for locking the supplemental base member in connection with said base when the parts of the pump are in operative position.

In testimony that I claim the foregoing as my invention I have signed my name in presence of the subscribing witnesses this 9th day of September, 1919.

PATRICK M. SCANLAN.
